UNITED STATES PATENT OFFICE.

FRITZ MOSER, OF ZOLLIKON, NEAR ZURICH, SWITZERLAND, ASSIGNOR TO WALTER SCHINDLER, OF BERNE, SWITZERLAND.

BUILDER'S HOISTING DEVICE.

Application filed March 26, 1923. Serial No. 627,770.

To all whom it may concern:

Be it known that I, FRITZ MOSER, a citizen of the Republic of Switzerland, residing at Zollikon, near Zurich, Switzerland, have invented certain new and useful Improvements in Builders' Hoisting Devices, of which the following is a specification, reference being had therein to the accompanying drawing.

10 Builders' hoists adapted to be attached to scaffolds of a building to be erected are known which are provided with a crane, the arrangement being such that according to requirements either the crane or the hoist 15 may alternately be utilized, the crane and the hoist being operated by the same driving motor. Devices of this type present the disadvantage that in addition to the jib of the crane there has to be a separate structure for mounting the guide rollers or on 20 the jib of the crane there has to be separate guide rollers for the hoist. Therefore either two lifting ropes, one for the crane and the other for the hoist are required or in case 25 only one rope is provided, this rope has to be taken off one of the lifting devices and to be placed over the rollers of the other lifting device and to be fixed to the latter when a change in the utilization of the 30 devices has to be made. This involves of course a tedious work that takes up much time during which the whole hoisting device cannot be utilized.

35 This disadvantage is overcome by the subject matter of the present invention, i. e., a hoisting device having guide means for the hoist-cage, above which guide means a swingable jib of a crane is so arranged that the same lifting rope running over guide 40 rollers provided on the swingable jib of the crane is used whether the hoisting device is operated as crane or as hoist.

With this device a single lifting rope is only required which runs over the jib of the crane and carries the hoist-cage or platform. The crane may be made ready for use in a very short time by merely unhooking the rope from the hoist-cage.

Several constructional examples of the

subject matter of the present invention are 50 illustrated in the accompanying drawings, in which:

Fig. 1 shows in an elevation view the complete hoisting device,

Fig. 2 is a plan view of Fig. 1,

Fig. 3 shows a detail on an enlarged scale and

Fig. 4 is a side view of the crane.

Fig. 5 illustrates in a side view a modified design of the hoist-cage.

Fig. 6 shows in an elevation view a second constructional example of the hoisting device.

Fig. 7 is a plan view of Fig. 6.

Fig. 8 is a plan view corresponding to 65 that of Fig. 7 with parts differently arranged.

Fig. 9 shows a third constructional example in elevation and Fig. 10 is a plan view thereof;

Fig. 11 shows a detail and

Fig. 12 is a detail modification.

Fig. 13 is an elevation view of the winch.

Fig. 14 is an elevation view of a detail modification.

Fig. 15 is a plan view of Fig. 14.

Fig. 16 is a detail on an enlarged scale.

With the hoisting device illustrated in Fig. 1, 1 denotes the rigid guide means consisting of several lengths of T-irons lap-jointed together by means of straps 11 and having their webs pointing towards each other. These guide means or rails are fixed to the finished outer wall of a building by means of holding straps 2 and stays 3 and are so arranged that a line passing through the webs of the T-irons (indicated in dotted lines in Fig. 3 of the drawing) is at right angles to the face of the wall. The hoist-cage 4 moves along the guide rails and is suspended from the lifting rope 5 which runs over the rollers 6 and 7 of the crane 8 and over a guide roller 9 situated at the ground level and is fixed to a winch 10 arranged at the ground level in the interior 90 of the building. The uppermost length of the guide rails which is joined by means of straps 11 to the lower length of the guide

rails is provided with the holding straps 2 between which a channel-iron 12 (Figs. 2 and 3) is fixed; the web of the channel-iron 12 being slotted over the greater part of its 5 length. A screw bolt 13 with which a nut provided with a handle 14 co-operates serves to connect the channel-iron 12 to the girder 15 of the structure of the crane. Owing to this arrangement the connection between the 10 upper length of the guide rails and the crane may be effected without it being necessary to place the crane at a definite level determined by the uppermost length of the guide rails. Upon the height of the building 15 increasing it will be necessary to place the crane at a higher elevation. In order to effect the connection between the crane structure in its new position and the guide rails a new length of rails is inserted below 20 the length of rails carrying the channel-iron 12, the slot in the web of the channel-iron enabling a connection between the guide rails and the crane structure by means of the screw bolt 13. The crane may be utilized 25 independently of the guide rails 1 and of the hoist by simply unhooking the lifting rope from the hoist-cage. As will be seen in Fig. 2 the jib of the crane, when the latter is utilized without the hoist, can be 30 swung through a comparatively large angle, so that a lifted load can easily be set down on the building. Owing to the fact that the crane pillar is arranged at a considerable 35 lateral distance from the guide rails of the hoist, these guide rails do not hinder the hoisting and setting down of loads which require much space. When the crane is adapted to be utilized for hoisting loads the lifting rope having a hook at its lower end 40 hangs freely from the roller 6, the hook being at other times in engagement with the hoist-cage.

In order to prevent the load from being hoisted too high or in order to cause the 45 hoisting to be interrupted at a certain elevation an adjustable stop 17 is provided on the lifting rope which knocks against a member 18 mounted on the axle of the lower guide-roller 9 and operatively connected to the 50 controlling gear of the winch. This connection consists of a rod 32, a bell-crank lever 33. (Figs. 1 and 13) and control-lever 34. The latter is operatively connected to a cone 55 coupling one part 36 of which is slidably arranged on the shaft 38 on which the drum 10 of the winch is fixed; the other part 37 of the cone coupling being rigidly fixed to a gear wheel 39 that is rotatably mounted on the drum shaft 38. When the stop 17 knocks 60 against the member 18 the latter is depressed whereby the rod 32 is moved towards the left in Fig. 1, the bell crank lever 33 is turned and causes a turning movement of the controlling lever about its fulcrum 65 whereby the cone coupling is disengaged and

the winch stopped. 40 denotes the driving belt-pulley of the winch, which pulley is rotated by the electric motor 41.

In the modified construction illustrated in Fig. 5 the hoist-cage is so constructed that 70 the suspension point is situated vertically above the centre of gravity. This is attained by fixing the lifting rope to the end of the part 16 projecting from the rear wall of the cage, and prevents the load from causing a tilting moment by which the lower 75 guide rolls 17 of the hoist-cage are pressed against the guide rails which would cause increased wear of the latter and a greater 80 moving resistance.

With the described arrangement of the hoist-cage the latter is adjacent the front of a building and can be brought into any desired elevation and unloaded there without 85 requiring any special scaffolding or platforms.

The above described constructional example of the builder's hoist may advantageously be utilized when erecting large buildings with which the space available for arranging a hoist is comparatively small. The position of the hoist-cage with regard to the building is however not very favourable; the following constructional examples of builders' hoisting devices present improvements 90 in this respect.

Fig. 6 shows in an elevation view a builder's hoist erected at the front of a house. 1 denotes the guide rails of T-section which are so arranged that the plane passing through the webs of both rails forms an angle of 45° with the face of the wall. The rails 1 are held together and fixed to the wall by means of holding straps or stirrups 2. The platform 4 of the hoist-cage 19 is 100 of a trapezoid shape when seen in plan view, i. e., its outer sides slope at an angle of 45° towards the parallel sides so that the side adjacent to the face of the wall is parallel to the latter. The pillar 8 of the crane structure is mounted on the foundation plate 20 and it can be fixed to the right hand facing 21^a of the plate 20 as is shown in Fig. 7 or to the left hand facing 21^a as is shown in Fig. 8. According to local conditions the hoist may in this manner be situated either to the left or to the right of the crane pillar 8. When the height of the building increases the guide means are 110 lengthened in the manner described above with the first constructional example. The arrangement of the lifting rope and of the winch is the same as in the first constructional example.

When erecting small buildings such as dwelling houses and the like, it is somewhat tedious and expensive to erect the above described rigid guide means. With small buildings the hoisting device according to Figs. 9-11 is therefore preferably adopted.

With this constructional example the guide rails 1 are replaced by a hemp or wire guide rope 21. One end of this rope is fixed to an eye-bolt 22 provided in the lower part 5 of the building and the rope is led over an upper guide roller 23 the diameter of which corresponds to the horizontal distance between the guide sleeves 24 of the hoist-cage 19. The other end of the rope is fixed to 10 the drum of a winch 25 on which drum a suitable number of spare-windings of the rope are arranged. The winch 25 is well anchored to the ground, however, the winch might be replaced by any other suitable 15 means for holding the rope end. The upper guide roller is swingably attached to a jib 26, the latter being rotatably mounted about a vertical pivot provided in the foundation plate 20 and being fixed in two angular positions 20 one of which is indicated in full lines, and the other is indicated by a dotted line in Fig. 10. The rope passing through the guide sleeves 24 of the hoist-cage serves as 25 guide means for the latter and it can be well tensioned by means of the winch 25. In order to place the jib 26 at a higher level and to lengthen the guide means when the 30 erection of the building advances, it is sufficient to unwind a few of the rope windings on the drum of the winch 25.

It will be seen in the plan view in Fig. 10 that the crane pillar 8 can be set on either of the two facings 21^a of the foundation plate 20 so that the hoist will be to the right or to the left of the crane pillar as has been described above and shown in Figs. 7 and 8, the jib 26 being simply turned from its one extreme position into its other. The oblique sides of the platform of the hoist-cage are provided with locking devices 35 for preventing a lowering of the hoist-cage during the removal of loads from the latter. The locking device consists of a spring loaded bolt 27 which can be held in its inoperative position and which, when released, projects beyond the oblique side of the platform and abuts against suitable stops arranged on the building wall. In addition to these locking devices the foundation plate 40 20 is provided with projecting claws 28 co-operating with eyes 29 on the hoist-cage to limit the upward movement of the latter.

This constructional example presents the advantage that no supporting elements fixed 45 to the building wall or to scaffolds are required and that the height of the guide means may easily be adapted to the advancing height of building in lengthening the guide rope by unwinding it from the winch. The removal of wheel barrows and similar vehicles from the platform of the hoist-cage to the building is facilitated and it requires 50 a minimum of space as one can drive such vehicles from the platform to the wall and

along the latter without changing the direction to a large extent. 65

Instead of a single upper guide roller 23 for the guide rope two small guide rollers 30 mounted in a frame 31 (Fig. 12) may be advantageously used when the platform of 70 the hoist-cage is large, and when the distance between the guide sleeves is thereby increased. The frame 31 is suspended from the jib 26 in a similar manner as the guide roller 23. 75

In the constructional example illustrated in Figs. 14-16 a crane 8 provided with a jib is shown placed on the top of a building under construction. The winch with the drum 10 for operating the lifting rope 5 is in contradistinction to the other constructional examples attached to the crane. The means for guiding the hoist-cage consists of a rope 21 as in the example illustrated in Figs. 9-11, which is lead over the pulleys 30. The pulleys 30 are mounted on a horizontal part 42 of a structure fixed to a foundation frame 43 to which the crane is secured. The structure comprises two vertical stays 44 and 45 on which sleeves 46 and 47 are guided. The sleeves 46 and 47 carry a rod extending in the horizontal direction and forming the axle of a roller 48 and 49 respectively. The frame of the hoist-cage is provided with similar rollers 50 and 51 on 85 which the platform in the shape of a board is loosely placed. 90

The sleeves 46 and 47 are adjusted on the stays in such a height as will be found most convenient to remove the loads lifted by the 100 hoist. The lifting of the latter is so adjusted that the rollers 50 and 51 of the hoist cage are at exactly the same level as the rollers 48 and 49 on the structure, when the hoist cage is raised to its uppermost position. In this manner the hoist is conveniently unloaded by sliding the platform on which the load is placed, from the rollers 50, 51 to the rollers 48, 49. According to 105 the nature of the goods and according to the customs of a country the adjustment of the height of the rollers will have to be carried out, as in some cases loads are carried on the head which in other countries are carried on the shoulders. The present structure 110 enables to carry out this adjustment in a very convenient way. 115

I claim:

1. A builder's hoisting device comprising in combination, rigid guide means secured 120 to a building being erected, a hoisting cage arranged to travel on said guide means and a slewing jib-crane above said guide means arranged to the side of said means, two rope-pulleys on said crane maintained in their relation to one another, and a single rope guided by said pulleys under all conditions 125 of operation, said rope arranged to operate

said cage when connected thereto and also operating as a hoist when the crane and its pulleys are swung from said guide means without changing the angularity of the crane jib.

2. A builder's hoisting device comprising in combination, a rigid vertical track composed of a pair of guide rails secured to a building, a hoisting cage arranged to travel on said track, a slewing jib-crane above said

track and arranged to the side thereof, holding straps for sections of the track, the upper track section having a longitudinally slotted member connected between a pair of such straps, and bolting means passing through said slot to bolt said upper section to the crane structure. ¹⁵

In testimony whereof I affix my signature.

FRITZ MOSER.
